UNITED STATES PATENT OFFICE.

PHILANDER NORTON AND DAVID T. MAY, OF PORT WASHINGTON, NEW YORK, AS-
SIGNORS TO WESTERN ELECTRIC COMPANY, INCORPORATED, OF NEW YORK, N. Y.,
A CORPORATION OF NEW YORK.

SELECTIVE SYSTEM.

Application filed December 29, 1923. Serial No. 683,297.

To all whom it may concern:

Be it known that we, PHILANDER NORTON and DAVID T. MAY, citizens of the United States of America, both residing at Port Washington, in the county of Nassau and State of New York, have invented certain new and useful Improvements in Selective Systems, of which the following is a full, clear, concise, and exact description.

10 This invention relates to selective systems, and more particularly to means for causing the selective operation of electro-responsive devices, such as telephone ringers, relays, etc.

15 The object of the invention is to simplify such systems and improve their operating efficiency.

20 The principal feature of the invention resides in inserting an electric discharge device in series with the device to be selectively operated, said discharge device having the characteristics of preventing the passage of current below a specified voltage, of passing current when 25 the voltage is increased beyond this point and of interrupting the current when the voltage falls below a certain other value.

25 The invention will be more clearly understood from the following description and 30 drawings, Fig. 1 of which represents what is known as a four-party selective ringing system embodying the invention and Fig. 2 represents a modification of the invention as applied to miscellaneous electromagnetic 35 devices, such as relays, etc.

35 In selective ringing telephone systems wherein positive and negative pulsing currents are transmitted over one or the other of the line conductors to selectively actuate 40 one of a plurality of telephone ringers connected between one side of the line and ground, it has heretofore been found desirable to only connect the ringers to the line when a ringing signal is to be transmitted. In practice this has been effected 45 by bridging a relay in series with a condenser across the two line conductors for each ringer and causing each relay to control the connection of its associated ringer 50 with the proper side of the line when ringing current is applied thereto. Such a system is shown in U. S. Patent 644,647 to

Messrs. Thompson and Robes, dated March 6, 1900. A modification of this system is in use wherein the bridged relays are 55 omitted and each ringer is connected between the line conductors and ground in series with an arrangement consisting of a condenser and a high resistance connected in parallel.

60 In accordance with the present invention the latter arrangement is modified by replacing the condenser and high resistance in series with each ringer, with a vacuum discharge device of the type such as has 65 been well known for a number of years in lighting which consists of alkaline metal electrodes inclosed with a rare gas in a sealed tube and which has the characteristic of preventing the passage of current 70 when the voltage is below a specified given low value, of passing current when the voltage is increased beyond this point, and of interrupting the current when the voltage falls below a certain other value. The 75 electrodes in this case, however, are placed relatively close together instead of a considerable distance apart as is necessary when the object is to provide illumination. This close spacing reduces the voltage re- 80 quired to break down the discharge gap.

Referring to the drawings C (Fig. 1) represents a telephone switchboard cord circuit arranged for four-party selective ringing, that is, keys K, K², K³ and K⁴ are 85 arranged when operated to apply either negative or positive pulsating current to either one side or the other of the line L. R⁴, R³, R² and R are biased telephone 90 ringers of a well known type, R⁴ being biased to respond to positive pulsating current flowing in the line conductor L¹, R³ being biased to respond to negative pulsating current in the line conductor L¹, and R² and R¹ being biased to respond to positive 95 and negative pulsating current respectively in the line conductor L².

Ringers R⁴, R³, R² and R are each connected between one side of the line L and ground in series with electrical discharge 100 devices 1, 2, 3 and 4, respectively. The operation is as follows: Let it be assumed that plug P has been inserted in jack J and that key K⁴ has been operated to connect

positive pulsating current to the ring conductor L^1 of the line and to connect ground to the tip conductor L^2 . This current will therefore traverse the line L^1 and if of sufficient strength will break down the discharge path between the electrodes of the devices 1 and 2, and traverse the windings of parallel ringers R^4 and R^3 to ground.

R^4 being biased to respond to pulsating current of positive polarity will actuate its armature in synchronism with the current pulsations and cause the bell to ring. R^3 however, having a negative bias does not respond.

15 It will be noted that ringers R^2 and R receive no current since the line conductor L^2 is grounded at key K^4 .

In a like manner key K^3 when operated connects negative pulsating current to conductor L^1 which causes ringer R^3 to respond to the exclusion of ringer R^4 , and keys K^2 and K^1 when operated connect positive and negative pulsating current respectively to conductor L^2 which causes the selective operation of their respectively biased ringers R^2 and R .

Due to the normal open circuit character of devices 1, 2, 3 and 4 the ringing apparatus associated with the line does not affect either the voice frequency current, or the low voltage currents used for signaling, which may pass over the line.

In accordance with another modification of the invention, Fig. 2 shows one of the discharge devices, heretofore described, employed to secure marginal operation of any electromagnetic device, such, for example, as relay 25, which may control the operation of mechanism for the return or collection 40 of a coin at a telephone coin box station.

In such systems, as is well understood in the art, the collection or refund of the coin is controlled by applying to the line either positive or negative direct current of a considerably higher voltage than the regular central office battery used for signaling and conversation. In practice, the voltage of such a source is about 110 volts.

Associated with the coin box at the subscriber's station and connected to the tip conductor of the line is a marginal polarized relay adapted to move its armature in one direction or the other depending on whether positive or negative current from the high voltage source is applied to that side of the line at the central office. The function of this armature is to either collect or refund the coin deposited by the calling party. In practice the requirements of this relay are that it must operate at approximately 60 volts, must not operate on 40 volts and must, when in an operated condition, release on 30 volts. Such margins are rather difficult to maintain.

65 Applying the present invention to such a

system, 22 represents the usual central office battery associated with an operator's cord circuit terminating in a plug P^2 adapted to be inserted in the jack J^2 of a subscriber's line 23, 24. 25 is the polarized relay associated with the subscriber's coin box (not shown), which relay has an armature 26 adapted, when operated, to control the collection or refund of a coin 27 inserted by the calling party. Connected in series with the polarized relay 25 is a discharge device 28 of the type before described, which can be so adjusted as to prevent the passage of a 40 volt current but which will pass current when the pressure is increased to 60 volts and will interrupt the current when the voltage is reduced to 30 volts. Associated with the operator's cord circuit are keys 29 and 30, which, when operated, apply either positive or negative 110 volt direct current from the generators 31 and 32, respectively, to the tip conductor 23 of the line.

It will be observed that, by employing the discharge device 28 in the manner suggested, it is not necessary that the polarized relay 25 be adjusted for marginal operation as current is not connected with the relay until such time as its operation is desired. In other words, the marginal condition is taken care of in the discharge device.

Other applications of a discharge device of this character to secure marginal operation of electromagnetic devices in electrical circuits will present themselves to those skilled in the art without departing from the spirit of the present invention.

What is claimed is:

1. In a selective signaling system, a line, a plurality of electrically operated signaling devices associated therewith, a plurality of sources of current of different voltage, means for applying said different voltage sources to said line, means for differently applying one of said voltage sources to said line to cause the selective operation of said signal devices, and a discharge tube in series with each of said devices so constructed and arranged as to conduct current of a certain voltage value, of a greater value, but not of a value lower than said certain value.

2. In a selective signaling system, a line, a plurality of electrically operated signaling devices associated therewith, a plurality of sources of current of different voltage, means for applying said different voltage sources to said line, means for differently applying one of said sources to said line to cause the selective operation for said signal devices, and a discharge tube in series with each of said devices so constructed and arranged as to conduct current of a certain voltage value, of a greater value, but not of a value lower than said certain value, said discharge device comprising a sealed receptacle containing a rare gas and electrodes, containing al-

kaline metal, relatively closely spaced with respect to each other.

3. In a telephone signaling system, in combination, a line, means for transmitting intermittent current of definite direction over one conductor of said line, an earth branch including a polarized bell connected with said conductor, said polarized bell having its armature biased to move in one direction with each current impulse and in an opposite direction with each interruption of said current, and an electric discharge device in series with said bell in said branch.

4. The combination, in a telephone signaling system, of a metallic line circuit, a source of intermittent current of definite direction connected to one of the conductors thereof, a subscriber's signaling apparatus comprising a polarized bell connected in a branch circuit between said conductor and ground, said bell being biased to vibrate in response to said definite direction current, and an electric discharge device, comprising a sealed receptacle containing an alkaline metal electrode and a rare gas, in series with said polarized bell in said branch circuit.

5. In a telephone signaling system, the combination with one conductor of a metallic line circuit, of means for transmitting an intermittent current of definite direction over said conductor, of an earth branch of said conductor serially including a polarized ringer biased to respond to said intermittent current of definite direction, and an electric discharge device comprising a sealed receptacle enclosing an alkaline metal electrode and a rare gas.

6. In a selective signaling system, line conductors, a plurality of biased signaling devices connected thereto, a signaling current generator adapted to transmit an intermittent current of definite direction over one of said line conductors, and an electric discharge device comprising a sealed receptacle containing an alkaline metal electrode and a rare gas in series with each of said signaling devices.

7. In a selective signaling system, a metallic line circuit, a plurality of biased ringers connected thereto, a source of signaling current for transmitting an intermittent current of definite direction, an electric discharge device comprising a sealed receptacle, containing an alkaline metal electrode and a rare gas, in series with each of said ringers, and switching means for connecting said source to one of said conductors.

8. In a selective signaling system, a metallic circuit telephone line terminating in a central office, a plurality of subscriber's stations connected thereto, a biased ringer individual to each subscriber's station, two of said ringers being connected to each line conductor, the two ringers which are connected to the same conductor being oppositely

biased, a signaling current generator for transmitting either positive or negative pulsating current, switching means for connecting either said positive or negative current to either of said line conductors, and an electric discharge device comprising a sealed receptacle containing an alkaline metal electrode and a rare gas in series with each of said biased ringers.

9. In a telephone signaling system, the combination with one conductor of a metallic line circuit, of means for transmitting an intermittent current of definite direction over said conductor, and an earth branch of said conductor serially including a polarized ringer biased to respond to said intermittent current and an electric discharge device comprising an evacuated vessel containing two electrodes relatively closely opposed.

10. In a selective signaling system, a metallic line circuit, a plurality of biased ringers connected thereto, a source of signaling current for transmitting either positive or negative pulsating current, an electric discharge device, comprising an evacuated vessel containing two relatively closely opposed electrodes, in series with each of said ringers, and switching means for connecting said source to one of said conductors.

11. In a selective system, a line, a device to be selectively operated connected thereto, a plurality of sources of current of different voltage, switching means for applying said different voltages to said line, and a discharge tube in series with said device, so constructed and arranged that it will maintain the energizing circuit of said device open during application to the line of certain of said voltages below a certain value, and will close said circuit upon the connection to said line of a source of voltage above said certain value.

12. In a selective system, a line, a device to be selectively operated connected thereto, a plurality of sources of current of different voltage, switching means for applying said different voltages to said line, a discharge tube in series with said device comprising a sealed receptacle containing a pair of electrodes and a rare gas, said device being so constructed and arranged that it will maintain the energizing circuit of said device open during application to the line of certain of said voltages below a certain value, and will close said circuit upon the connection to said line of a source of voltage above said certain value.

13. In a selective system, a line, a device to be marginally operated connected thereto, a plurality of sources of current of different and comparatively low voltage, switching means for selectively applying said different voltages to said line and a discharge tube in series with said device so constructed and ar-

ranged as to prevent current applied to the line from energizing said marginal device when a voltage of said current is less than a certain value, to pass current to energize 5 said device when the voltage of the current applied is above said certain value and to interrupt said current flow when the voltage

of the current present in the line is reduced below a certain other value.

In witness whereof, we hereunto subscribe 10 our names this 22d day of December, A. D. 1923.

PHILANDER NORTON.
DAVID T. MAY.
